UNITED STATES PATENT OFFICE.

EDGAR D. JOHNSON, OF EAST ORANGE, NEW JERSEY, ASSIGNOR TO WESTERN ELECTRIC COMPANY, INCORPORATED, OF NEW YORK, N. Y., A CORPORATION OF NEW YORK.

REPEATER SYSTEM.

Application filed January 18, 1918. Serial No. 212,462.

To all whom it may concern:

Be it known that I, EDGAR D. JOHNSON, a citizen of the United States, residing at East Orange, in the county of Essex, State 5 of New Jersey, have invented certain new and useful Improvements in Repeater Systems, of which the following is a full, clear, concise, and exact description.

This invention relates to repeater circuits 10 in which a one-way repeater is reversibly connected in a transmission circuit to provide for the two-way transmission of signals.

An object of the invention is to provide 15 means for connecting the repeater in circuit automatically and in response to current such as voice current impressed on the line. This is accomplished, giving rise to a very 20 positive control of the circuit connections, by providing a voice-operated relay for each 25 of the two line terminals or sections, the operation of either relay in response to current impressed on its corresponding line section serving not only to connect the repeater 30 properly in circuit but also to change the connections of the other control relay so that 35 these relays will assist each other in maintaining the repeater properly connected. The assistance of the second or subsequently 40 operated relay is of material advantage, for this second relay in the embodiment chosen to illustrate the invention and its various 45 aspects, is connected in the output circuit of the repeater and accordingly energized by amplified current, whereas the relay initially 50 operated is in the input circuit of the repeater and is actuated by the comparatively feeble incoming current.

This will be described further in detail 55 in connection with the drawings, in which the figure represents diagrammatically one embodiment of the invention.

Referring to the drawings, the repeater 1, here shown as of the mechanical type, but 60 obviously any other type may be employed, is adapted to be reversibly connected to the line sections or the terminals 2 and 3, the electromagnetic switches 4, 5, 6 and 7 being employed to connect the repeater in such 65 manners that the two-way transmission of signals between the lines 2 and 3 is provided. The operation of the switches 4, 5, 6 and 7 is controlled by the intermediate relays 8, 9, and the latter are in turn controlled by the

control relays such as voice relays 10 and 55 11. The voice relays 10 and 11 are responsive to alternating or pulsating current, such as voice current, to cause the vibration of their normally closed contacts 12 and 13 respectively. The invention is not limited to 60 any particular form of voice relay, and as indicating one type of control relay that may be employed, reference is made to the patent to Brown, 1,185,472, telephony, May 30, 1916.

The solenoid of the voice relay 10 normally, that is, when no current is impressed on the line, is connected to the line 2 through armature 41, lead 42, armature 43, relay 10, armature 61, lead 62 and armature 63. The armatures 41 and 43 are held in contact with 70 the lead 42 by reason of the fact that the circuit of the solenoid of the switch 4 is completed through ground, battery 44, solenoid of switch 4, lead 14, armature 15 of relay 8, lead 16, closed contacts 13 of relay 75 11 and armature 17 of relay 9 to ground. The energizing circuit for the switch 6 may be traced from ground to battery 64, solenoid of switch 6 to point A. Energizing circuit of relay 8 may also be traced in part 80 to this point A from the ground through battery 21 and through the solenoid of relay 8. The energizing circuit of switch 5 may also be traced to this point A from ground, 85 battery 54 and through the solenoid switch 5. The switches 5 and 6 and the relay 8 are all connected to this point A, from which the circuit leads through armature 18 of relay 9, lead 19, closed contact 12 of relay 10 and armature 20 of relay 8 to ground. 90 The battery circuits for switches 4 and 7 and for the relay 9 may be readily traced 95 to the point B, from which the circuits extend as has already been traced for the switch 4 through armature 15 of relay 8, lead 16, contacts 13 of relay 11 and armature 17 of relay 9 to ground.

When no current is impressed on the lines 2 and 3, the voice relays 10 and 11 are de-energized and the solenoid of each of these 100 relays is included in circuit with its corresponding line or line section. Furthermore the repeater is entirely disconnected from both of the lines 2 and 3 as shown in the drawing.

When voice current is impressed on the line 2, the voice relay 10 sets its contact 12 into vibration, thereby materially increasing

the resistance in the circuit which leads from the ground to armature 20 of relay 8, contact 12 of relay 10 to lead 19, and armature 18 of relay 9 to the point A, from 5 which three parallel circuits lead through the switches 5 and 6 and the relay 8, thereby deenergizing the latter three. The deenergization of the switch 6 causes armatures 61 and 63 to assume their outermost positions, 10 thereby connecting the input circuit of the repeater 1 in series with the voice relay 10 and with the line 2. The deenergization of switch 5 connects the output circuit of repeater 1 in series with the line 3 and with 15 the solenoid of voice relay 11 which is thereby energized by amplified voice currents. Deenergization of the relay 8 has moved armature 15 to its alternate position, thereby connecting the point B to 20 ground through the armature 15.

This serves to remove the control of switches 4 and 7 and relay 9 from the voice relay 11. The deenergization of the relay 8 also moves armature 20 to its alternate 25 position, this serving to connect the contacts 12 of relay 10, and 13 of relay 11 in series between the ground and the point A over the following circuit: ground to armature 17, contact 13, armature 20, contact 12, 30 armature 18 to point A, from which the circuit extends to the deenergized switches 5 and 6 and the deenergized relay 8, these latter three being maintained effectively deenergized by reason of the fact that the 35 vibrating contacts 12 and 13 are assisting each other, being connected in series. The operation of the contact 13 is of material assistance, since the voice relay 11 is energized by amplified current derived from the 40 output circuit repeater 1, whereas the initially operated relay 10 is controlled by the comparatively feeble voice current coming over the line 2.

Upon the cessation of current originating 45 in line 2, the contacts 12 and 13 become quiescent, thereby decreasing the resistance in the circuit which extends from ground through armature 17, contact 13, lead 16, armature 20, contact 12, lead 19, armature 50 18 to point A, from which the circuit extends through the switches 5 and 6 and the relay 8. This decrease in the resistance between the point A and the ground, serves to sufficiently energize the switches 5 and 6 55 and relay 8 so that they attract their armatures to their normal positions shown in the drawing.

Relays 8 and 9 preferably have make-break contacts and are quicker in their 60 operation than switches or relays 4, 5, 6 and 7.

Since the circuits are symmetrical as seen 65 from lines 2 and 3, switches 4 and 6 and relays 8 and 10 being similar to the corresponding elements associated with the line

3, it is apparent that the operation of these devices as to current originating in line 3 will be similar to that above described.

What is claimed is:

1. The combination of a line, a repeater 70 adapted to be reversibly connected thereto, a relay for controlling the connection of said repeater to said line, and means comprising a relay and a vibratile contact controlled thereby whereby current derived 75 from the output circuit of said repeater is effective to control the repeater connections.

2. The combination of a line, two relays therefor, contacts for each of said relays, and means for rendering said contacts at 80 times independent and at other times co-operating.

3. The combination of a line, two relays therefor, contacts for each of said relays, and means for causing said contacts to be 85 at times included in independent electrical circuits and at other times in series in the same circuit.

4. In combination with a line, two voice-operated relays therefor, each having a vibrating contact, means connecting said contacts in independent circuits when said relays are deenergized, and means responsive 90 to the energization of either of said relays for causing said contacts to be connected 95 in series.

5. A line, a repeater therefor, two relays for controlling the connection of said repeater to said line, and means for causing 100 said relays to operate at times independently and at other times cooperatively.

6. A two-way repeating system comprising a line, a repeater therefor, two voice-operated relays for controlling the connection of said repeater to said line, and means 105 for causing said relays to operate independently at times and cooperatively at other times.

7. In a telephone system, the combination of a line, a repeater therefor, a relay comprising a solenoid and an armature for controlling the connections of said repeater to said line, and means comprising an armature movable independently of said first mentioned armature whereby current derived 115 from the output circuit of said repeater is effective to assist said relay in controlling the repeater connections.

8. The combination of two lines, a repeater adapted to be connected therebetween, 120 a relay responsive to current approaching the input of said repeater for controlling the repeater connections, and means for automatically connecting said relay to or disconnecting said relay from the output 125 circuit of said repeater.

9. A line, a repeater; a relay for controlling the connections of said line to said repeater, and means responsive to current impressed on said lines for connecting said 130

- relay to the output circuit of said repeater for transmission in one direction, and to the input circuit thereof for transmission in another direction.
5. 10. A two-way repeating system comprising two lines, a repeater normally operatively disconnected therefrom, a voice-operated relay normally connected to each of said lines, the energization of either of said 10 relays serving to connect said repeater to said lines for transmission in the proper direction and to connect the other relay for assisting the relay initially operated.
11. A two-way repeating system comprising two lines, a repeater therefor, a voice-operated relay for each of said lines, and connections whereby each of said relays respond to impulses coming in over its line to establish the repeater connections and 20 whereby both of said relays maintain the repeater connections.
12. A two-way repeating system comprising two lines, a repeater, reversing switching means between said repeater and said lines, 25 two voice-operated relays, each having a vibrating contact for controlling said switching means, said contacts being in independent circuits when said relays are deenergized, the energization of either of said relays serving (a) to connect one of said relays to the input circuit, the other to the output circuit of said repeater (b) to connect said vibrating contacts in series, and (c) to connect said repeater to said lines for transmission in the proper direction.
13. A line comprising two sections, a repeater adapted to be reversibly connected thereto, a voice-operated relay for each of said line sections for reversibly connecting 40 said repeater to said line, and connections whereby one of said relays is operated by current derived from the output circuit of said repeater.
14. A line, a repeater, a relay for controlling the connections of said line to said repeater, and means comprising a vibratile contact responsive to current impressed on said lines for connecting said relay to be energized by current from the output circuit of said repeater.
15. The combination of a solenoid, an armature controlled thereby, two relays therefor, contacts for each of said relays, one of said contacts being vibratile and connections 55 whereby said contacts may be cooperatively or independently included in circuit with said solenoid.
16. The combination of a solenoid, an armature controlled thereby, two relays therefor, vibratile contacts for each of said relays, and means whereby only one of said contacts may be effectively connected in circuit with said solenoid or whereby both of said contacts may be connected in series 60 therewith.
17. The combination of a line, electromagnetic switches therefor having armatures, a repeater, a relay controlling said repeater, said armature at times connecting the solenoid of said relay in circuit with said line to the exclusion of said repeater and at other times operatively connecting said repeater in circuit with said line and relay.
18. The combination of a line, a plurality of electromagnetic switches therefor each having two armatures, a repeater, a relay controlling said repeater, and circuit connections whereby said armatures at times connect the solenoid of said relay in circuit with said line, while leaving said repeater effectively disconnected therefrom, the armatures for one of said switches at times connecting the input side of said repeater to said line, the armatures for another of said switches at times connecting the output side of said repeater to said line.
19. The combination of two lines, a repeater adapted to be reversibly connected therebetween, and means comprising a relay for controlling the connection of said repeater to said lines, said relay being connected to the output side of said repeater for energization by amplified currents from said repeater.
20. The combination of two lines, a repeater adapted to be reversibly connected therebetween, a relay responsive to current approaching the repeater in either direction for controlling said repeater, and connections for energizing said relay with amplified current from said repeater.
21. A line, a repeater, means for operatively associating either the input side or the output side of said repeater with said line, and means responsive to amplified current from said repeater for controlling said first mentioned means.
22. A repeater system comprising two lines, a unidirectional current conducting amplifying means, switches for reversibly connecting said means to said lines, electromagnetic means for controlling said switches, and means, including a relay, for controlling said electromagnetic means and rendering said relay active at times in response to amplified current from said amplifying means and at times in response to current incoming into said amplifying means.
23. A repeating system comprising two lines, a repeater, switch contacts for reversibly connecting said repeater to said lines, a plurality of alternating current relays for controlling said contacts, means including connections for rendering one of said relays active at times in response to amplified outgoing currents from said repeater and at times in response to currents incoming into said repeater, and means whereby one of said alternating current relays controls another.

24. Two line sections, a device to be connected therebetween, two relays having windings and having armatures disconnected from each other and individual to 5 said windings, means for connecting each of said windings between said device and one of said sections, and means for causing one of said relays to establish the connection of said device to said line sections upon energization of said winding of said one relay, and 10 for causing both of said relays to maintain the connection of said device to said line sections while said windings are energized.

25. A repeating system comprising a relay having a vibratable contact, a circuit to 15 be controlled thereby, an auxiliary relay assisting said first-mentioned relay, and a

circuit comprising a contact operating continually while repeating and controlled by 20 said relays.

26. A signaling system comprising a repeater, a line, and means for reversibly connecting said repeater thereto, said means including two sets of relatively movable contacts connected in series, a solenoid in series 25 with one set for holding said other set closed, and a solenoid responsive to alternating voltage on said line for operating said one set.

In witness whereof, I hereunto subscribe my name this 14th day of January, A. D., 1918.

EDGAR D. JOHNSON.
